UNITED STATES PATENT OFFICE.

WILLIAM JOE KRAMER, OF ST. LOUIS, MISSOURI.

INCLOSED OR CARTRIDGE FUSE.

1,388,269.

Specification of Letters Patent. Patented Aug. 23, 1921.

Application filed June 16, 1919. Serial No. 304,481.

To all whom it may concern:

Be it known that I, WILLIAM J. KRAMER, a citizen of the United States, residing at the city of St. Louis, State of Missouri, have 5 invented a certain new and useful Improvement in Inclosed or Cartridge Fuses, of which the following is a specification, reference being had to the accompanying drawings, forming a part thereof.

10 This invention relates generally to electric safety fuses and, more particularly, to a certain new and useful improvement in that class of electric safety fuses commonly known as renewable inclosed or cartridge fuses.

15 The principal object of my present invention is to provide an inexpensive and efficient fuse of the class and especially of the type mentioned comprising readily and conveniently assembled and disassembled parts, and in which the fusible-element or strip may be quickly renewed when blown or disrupted by an excess of current, the more expensive casing or shell and terminals or 20 other fittings of the fuse being retained and repeatedly used.

25 With the above and other objects in view, my present invention resides in the novel features of form, construction, arrangement, and combination of parts hereinafter described and afterward pointed out in the claims.

In the accompanying drawing,

30 Figure 1 is an elevational view, partly in longitudinal section, of a fuse constructed in accordance with and embodying my invention;

35 Fig. 2 is a similar view of the fuse taken approximately at right angles to Fig. 1;

40 Fig. 3 is a perspective view of the inner or inclosed members of the fuse in disassembled but associated relation, ready for assembling;

45 Fig. 4 is a similar view of the so-called outer or terminal members for one end of the fuse;

50 Fig. 5 is a transverse sectional view of the fuse taken approximately on the line 5—5, Fig. 1;

55 Fig. 6 is a perspective view of a slightly modified form of one of the end-closing members of the fuse for adapting the same to the ferrule-type; and

60 Figs. 7 and 8 are longitudinal and transverse sectional views, respectively, of a fuse of the plug type, showing the adaptation

therefor of the fusible-strip or element holder of the present fuse.

Referring now more in detail to the said drawings, in which like reference characters refer to like parts throughout the several views, 1 indicates the fuse casing, which is preferably an open-ended tubular shell of fibrous or other suitable insulation material, and which may be of any suitable 65 length and diameter as required according to the desired size or current-carrying capacity of the fuse.

Threaded to seat permanently upon the shell 1 at its opposite ends, are tubular 70 metallic ferrules 2—2, each provided internally and intermediate its ends with an annular shoulder or flange 3 adapted at one or its inner face to abut against the end of the shell, as seen especially in Figs. 1 and 2, 75 and at its other or outer face to form an abutment or seat for parts hereinafter appearing. 4 indicates as a unit what I might designate the fusible-strip holder. This holder 4 is substantially a tubular casing 80 longitudinally split into and comprising two separate, matching, and co-operating semi-cylindrical insulation members 5—5, each at its opposite ends provided with, and embedded in, a semi-cylindrical ferrule 6, the 85 ferrules 6 having each an approximately semi-cylindrical solid tongue 7 disposed within and providing plug-terminals for the members 5, as seen especially in Fig. 3. Adapted to fit renewably within the holder 90 4, is a fusible element or strip 8, which may be of any suitable readily fusible metal or alloy, and which is of the desired ampere carrying-capacity, as will be well understood. This strip 8 is of a length somewhat 95 less than the length of, and to fit within, the holder 4, the members 5 of the holder being adapted, in use, for longitudinal disposition upon the opposite flat faces of, and to correspondingly surround, the strip 8 and 100 to engage electrically at the tongues 7 of their ferrules 6 with the strip.

The holder 4 is of reduced size, both in length and diameter, relatively to the shell 1, the holder 4 being adapted to fit longitudinally of and within the shell 1, as illustrated in Figs. 1 and 2; and to removably support and position the holder 4 within the shell 1, I provide sleeves 9—9 adapted to fit within the shell and each having at its 105 outer end an annular outstanding flange 10 adapted to seat or engage at their inner face

upon the outer face of the ferrules-flanges 3, as also seen especially in Figs. 1 and 2. The sleeves 9 are adapted to fit tightly, but removably, upon and engage the holder 4 at its ends, the sleeves 9 not only thus engaging electrically with the ferrules 6, but also firmly retaining the holder-members 5 operatively around the strip and their ferrules 6 in electrical contact therewith. As the inclosed strip 8 may occasionally vary in thickness, the sleeves 9 are preferably provided longitudinally with a plurality of kerfs, as at 11, whereby the sleeves 9 are adapted to yield to accommodate in their engagement with the holder 4 strips 8 of varying thickness between the holder-members 5.

Disposed within each ferrule 2 and flatwise upon the outer face of the sleeve-flange 10, is a closure disk 12 for the shell; and threaded into each ferrule 2 to engage the disk 12 and rigidly hold or clamp the disk 12 in electrical engagement with the sleeve-flange 10 and the sleeve 9, in turn, at its flange 10, in electrical engagement with the ferrule-flange 3, is an externally or circumferentially threaded ring 13 provided preferably with suitable recesses or the like 14 for convenient engagement by a spanner-wrench or the like, not shown.

In the so-called knife-blade type of fuse, the disks 12 are integrally or otherwise suitably provided with knife-blade terminals 15 rigidly projecting outwardly of the shell. In the so-called ferrule type of fuse, such terminals may be omitted and plain disks, such as the disk 12^a illustrated in Fig. 6, substituted as and for the disks 12. Thus the fuse may be conveniently adapted for either type.

In assembling the parts of the fuse, the ferrules 2 are fixed upon the shell 1, as described. A strip 8 is then placed lengthwise between the holder-members 5, and a sleeve 45 9 fitted into engaging position upon the ferrules 6 thereof. The sleeve 9 and holder 4 are then inserted endwise into the shell from one end and the flange 10 of the sleeve 9 brought into engagement with the flange 3 of the ferrule 2 at such end of the shell. The other sleeve 9 is then inserted endwise into the opposite end of the shell and into engaging position upon the corresponding ferrules 6 of the holder 4, and its flange 50 10 seated upon the ferrule-flange 3 at such end of the shell. The disks 12 and rings 13 are then, respectively, seated within and engaged with the ferrules 2, when the fuse is ready for use, the holder 4 being in electrical contact with the strip 8 and the sleeves 9 being in electrical contact with the holder 4 and with the disks 12 and ferrules 2, as before described. On a blowing or disruption of the strip 8 on an excess of current, 55 it will be evident without further explana-

tion that, on removal of the retaining-rings 13, the other inclosed parts of the fuse may be readily removed from the shell 1, a new strip 8 substituted within the holder 4, and the parts again assembled as described, the shell and all the other parts of the fuse being retained and repeatedly used.

My fuse embodies few, inexpensive, and readily manufactured parts, which may be quickly and conveniently assembled and disassembled, as will be obvious from the foregoing description; the contacting-surface between the current carrying parts of the fuse is relatively large; and the parts are securely held together and from being blown off or from the shell on a disruption of the fusible-element or strip.

I am aware that changes in the form, construction, arrangement, and combination of the several parts of the fuse may be made and substituted for those herein shown and described without departing from the nature and principle of my invention. And as showing a modified adaptation or use of the holder of the fuse-strip, I have illustrated the same in Figs. 7 and 8 in connection with a fuse of the plug type. In this type of fuse, the holder-members 5'-5', surrounding and electrically engaging with the strip, as before described, are held operatively together by, and are in electrical engagement at their ferrules 6' with, spring-clips 16-16' suitably mounted within the shell or body 17 of the fuse and, in turn, suitably electrically connected with the end and side terminals 18 and 19, respectively, of the fuse, the shell 17 being closed at its upper or open end by a suitable cap 20.

Having thus described my invention, what I claim and desire to secure by Letters Patent is:

1. In a renewable fuse, a tubular fuse-strip holder including a pair of semi-cylindrical insulation members separate one from the other and adapted for coöperation to 110 separably fit longitudinally upon the opposite flat faces of and correspondingly surround a fuse-strip, and terminals fixed on the ends of said members for removably supporting, and engaging electrically with the 115 ends of the strip.

2. In a renewable fuse, a tubular fuse-strip holder including a pair of semi-cylindrical insulation members separate one from the other and adapted for coöperation to 120 separably fit longitudinally upon the opposite flat faces of and correspondingly surround a fuse-strip, and semi-cylindrical plug-terminals fixed on the ends of said members for removably supporting and engaging electrically with the ends of the strip.

3. In a renewable fuse, a tubular fuse-strip holder including a pair of semi-cylindrical insulation members separate one from 125

the other, and ferrules fixed on said members and having semi-cylindrical tongues disposed within and plugging the ends of said members, said members being adapted 5 for coöperation to separably fit longitudinally upon the opposite flat faces of a fuse-strip and to engage electrically therewith at said tongues.

4. A renewable fuse including a tubular 10 fuse-strip holder comprising a pair of semi-cylindrical insulation members separate one from the other and adapted for coöperation to separably fit longitudinally upon the opposite flat faces of and correspondingly surround a fuse-strip, and ferrules fixed on the ends of said members and having tongues disposed within said members for removably supporting and engaging electrically with the ends of the strip, in combination 15 with conducting-members adapted for detachable engagement with the ferrules to separably maintain the holder-members and the strip in operative relation.

5. A renewable fuse comprising a shell 20 and tubular ferrules fixed on the ends of the shell, in combination with a fuse-strip holder having current-conducting terminals fitting removably longitudinally within the shell, conducting retaining-members for the 25 holder also fitting removably within the shell and engaging loosely with the ferrules and detachably with the holder, and closure-means for the ends of the shell having detachable engagement with the ferrules.

30 6. A renewable fuse comprising a shell and tubular ferrules fixed on the ends of the shell, in combination with a fuse-strip holder having current-conducting terminals fitting removably longitudinally within the shell, conducting retaining-sleeves for the 35 holder also fitting removably within the shell and engaging loosely with the ferrules and detachably with the terminals of the holder, and means having detachable engagement 40 with the ferrules for locking the shell, sleeves, and holder operatively together.

7. A renewable fuse comprising a shell, a 45 fuse strip, and tubular ferrules fixed on the ends of the shell, in combination with a two-piece separable fuse-strip holder having current-conducting terminals fitting removably within the shell, conducting retaining-sleeves also fitting removably within the

shell and engaging loosely with the ferrules, said sleeves also embracing and engaging 55 electrically with said terminals for separably maintaining the holder-parts and the fuse-strip in operative relation, and means including disks fitting removably in the ferrules for detachably locking the shell, 60 sleeves, and holder operatively together.

8. A renewable fuse including, in combination, a shell, tubular ferrules fixed on the shell, a two-piece fuse-strip holder having current-conducting terminals disposed 65 removably within the shell, a fuse-strip disposed renewably between, and engaging electrically with the terminals of, the members of the holder, and means including members engaging electrically with said terminals and disks fitting removably within the ferrules for operatively retaining the holder and surrounded strip operatively together and within the shell.

9. A fuse comprising a shell and flanged 70 ferrules on the ends of the shell, in combination with a two-piece fuse-strip holder adapted to fit longitudinally within the shell, flanged retaining sleeves for the holder adapted also to fit within the shell and to 75 engage at their flanges with the flanges of the ferrules, said sleeves being adapted to embrace the holder for holding the parts thereof together and to engage electrically therewith, and end-members for the shell 80 fitting within the ferrules and having engagement with the sleeves.

10. A fuse comprising a shell and flanged ferrules on the ends of the shell, in combination with a two-piece fuse-strip holder 90 adapted to fit longitudinally within the shell, a fuse-strip disposed renewably within the holder and electrically engaging therewith, flanged retaining-sleeves for the holder 95 adapted also to fit within the shell and to engage at their flanges with the flanges of the ferrules, said sleeves being adapted to embrace the holder for holding the parts thereof together and to engage electrically therewith, disks fitting within the ferrules and 100 engaging the flanges of the sleeves, and securing washers for the disks having engagement with the ferrules.

In testimony whereof, I have signed my name to this specification.

WILLIAM JOE KRAMER.
